UNITED STATES PATENT OFFICE.

RAY E. HALL, OF ROCK ISLAND, ILLINOIS, ASSIGNOR TO HALL RESEARCH CORPORATION, OF CHICAGO, ILLINOIS, A CORPORATION OF DELAWARE.

METHOD OF AND MEANS FOR TRANSLATING SOUNDS.

Application filed May 8, 1922. Serial No. 559,170.

To all whom it may concern:

Be it known that I, RAY E. HALL, a citizen of the United States, residing at Rock Island, in the county of Rock Island and 5 State of Illinois, have invented certain new and useful Improvements in Methods of and Means for Translating Sounds, of which the following is a specification.

The object of this invention is broadly to 10 improve upon the subject matter of my prior Patents No. 1,160,072 granted November 9, 1915, No. 1,205,530 granted November 21, 1916, and No. 1,378,345 granted May 17, 1921.

One particular object of the invention is 15 to give the diaphragm or other movable medium a more steady and larger motion and to eliminate fluttering.

A further object of the invention is to increase 20 the sensitiveness of the relay by causing the contacts to open or close upon a change of direction of the movable medium as distinguished from a change of position.

A further object of the invention is to 25 provide means for regulating the pressure of the fluid used in the jet.

A further object of the invention is to produce 30 a compact device embodying the principles in a form that can be manufactured at relatively small cost.

Further objects of the invention will become 35 apparent as the description is read in connection with the accompanying drawing in which

Fig. 1 is a plan view of the invention, parts of the cover being broken away for the purpose of better illustration;

Figs. 2 and 3 are vertical sections on the lines 2-2 and 3-3 of Fig. 1 respectively; 40 and

Fig. 4 is a diagrammatic view illustrating one use of the invention.

Referring to the drawings 10 indicates a box or casing having suitable battens 11 secured to the top and bottom adapted to receive screws or other fastenings for holding the plate 12 thereto in the position indicated in Figs. 2 and 3. Secured to the side of this plate is a pair of tanks 13 and 14 adapted to receive the fluid for forming the jet. The fluid enters the tank 13 from a pump or blower 15 through the pipe 16 which extends a substantial distance into the tank as indicated in Fig. 3. The tanks 13 and 14 are connected by a U-shaped tube 17

having its ends extending well into the tanks away from the side walls to prevent sound vibrations from being transmitted from one tank to the other through the tube. A similar tube 18 connects the tank 14 with the nozzle 19 for forming the jet. The tank 14 is equipped with an outlet 20 leading through the plate 12 over which lies a flat valve 21 adapted to be adjusted by the screw 22 to permit more or less fluid to pass through the outlet. By closing this passage the pressure is made to rise in the tank 14 and consequently the jet formed by the nozzle 19 will be varied. In order to indicate the pressure in the tank 14 so that proper adjustments may be made I provide a manometer 23 which is here shown in the form of a horse shoe shaped tube 24 having the connection 25 extending into the tank 14. The horse shoe shaped portion of this tube lies over a scale 26 supported on the front side of the plate 12 which may bear any sort of graduations. As illustrated the graduations consist of horizontal lines suitably spaced apart and one of the lines is marked zero. By filling the tube until both sides of the horse shoe are at the level of the zero mark, suitable readings can be made upon the pressure in the tank 14 to permit the valve 21 to be adjusted to suit the particular needs of different situations.

Alongside the tanks 13 and 14 a frame 27 is secured to the plate 12 and forms a support for a sound producing device such as a wireless receiver 28 and for the nozzle 19. The wireless receiver 28 includes a diaphragm 29 which is connected by a funnel 30 with the jet 31. Preferably, the nozzle 19 is equipped with a cylindrical passage 32 at its end which gives the jet a cylindrical form, and the funnel 30 is preferably conical at the discharge end. The relation between the tip of the nozzle 19 and the funnel 30 can be varied somewhat but the best results will be had when the axis of the funnel 30 is substantially flush with the extreme end of the nozzle.

The jet 31 is here shown acting upon a diaphragm 33 formed of thin sheet rubber held to the outside of the plate 12 by the ring 34 through which the screws 34 pass into the plate. Between the active portion of the diaphragm and the plate 12 is interposed a disk 35 having a dish-shaped face presented to the diaphragm; the back of the

disk 35 is flat and may lie flush against the face of the plate 12. As shown the disk is equipped with a tube 36 passing through the boss 37 on the frame 27 and adjustably secured in place by the screw 38. The end of the tube 36 is equipped with a bracket 39 carrying a baffle 40 spaced somewhat from the end of the tube 36 and provided with a port 41. It is particularly important that the passage 42 in the tube 36 be larger than the port 41 and the passage 32 in the nozzle. Preferably the port 41 and the passage 32 are substantially the same size. When the diaphragm 29 of the wireless receiver is at rest the jet will proceed from the nozzle 19 through the port 41 and the tube 36 and impinge upon the rear side of the diaphragm 32. When a signal is received by the wireless receiver the jet will assume varying phases as the sound waves are impressed upon it, of which the dotted lines in Fig. 2 indicate one form. When the jet is undisturbed it passes through the baffle 40 and the passage 42 and distends the diaphragm 33 but when it assumes some such form as indicated practically none of the fluid goes through the port 41 and hence the pressure against the diaphragm 33 is relieved permitting it to assume normal, substantially flat position, or move in that direction an amount depending upon the duration of the signal.

A resilient arm 43 is secured to the ring 34 by the screw 44 and extends over the diaphragm to approximately the middle where it is fitted with a cap of insulating material 45. Adjacent to this cap is an angular conductor 46 having a contact 47 at the end thereof spaced from the insulating cap 45. A yielding plate 48 is also secured to the ring by the screw 44 and may be pressed down by the screw 49 to adjust the spring arm 43 downwardly towards the diaphragm.

Cooperating with the contact 47 is a movable contact 50 carried by a pivoted arm 51 which has a lateral bearing 52 mounted in the bracket 53 secured to the ring 34. This bracket has an arm 54 extending substantially parallel to the arm 51 and carrying a spring 55 which contacts with the pivot bearing 56 that is approximately aligned with the bearing 52. The arm 51 adjacent to the bearing 52 is provided with a flat face 57 adapted to have frictional engagement with the side face of the bracket. A screw 58 threaded through the end of the arm 54 and bearing against the end of the spring 56 can be adjusted to change the pressure between the face 47 and the bearing to vary the friction to be overcome in moving the arm 51.

By mounting the arm 51 in this manner it will tend to remain in any position of adjustment. Consequently, when the diaphragm has moved in one direction until

the spring arm 43 has engaged the arm 51 either with the cap 45 or the contact 47, a change in direction of movement on the part of the diaphragm will cause the arm 43 to shift its engagement to the other side of the arm 51, or to close or open a circuit. 70

In other words the making or breaking of contact between the conducting surfaces 47 and 50 will be controlled by a change of direction in the movement of the diaphragm 75 as distinguished from a change of position.

The resilient arm 43 is connected by a wire 59 with a binding post 60, and the arm 51 is connected to a binding post 61 through a wire 62, a switch 63 and a second wire 64. The switch 63 has an arm 65 which may make contact with the post 66 to which the wire 62 is connected or the dead post 67 to turn the apparatus on or off. In order to take care of any surge of current, the post 66 is connected to the post 60 through a coil 68 as indicated in dotted lines in Fig. 1. The binding posts 60 and 61 may be used to connect the apparatus with a recorder 70, or the like, as indicated on the diagram in Fig. 4. These binding posts are preferably carried on a cover of insulating material 71 secured to the casing 10 by the bolts 72. Binding posts 73 and 74 are also mounted on the cover and afford fastening for the cables 75 and 76 by which the wireless receiver may be connected with a receiving set 77. 80

By passing the jet through an enlarged passage like that shown at 42 and interposing the baffle 40 adjacent to the end of the passage the pressure against the diaphragm is immediately relieved as soon as the jet takes the form that will not pass through the port 41. The more the fluid in the jet is disturbed the less the fluid will pass through the port 41 and the more will be the relief of the pressure on the diaphragm. This makes the device much more steady 105 and sensitive and at the same time eliminates fluttering, which sometimes occurs. By combining this arrangement with the jockey arm 51, which gives a floating zero mark, 110

the apparatus becomes extremely accurate and sensitive giving very quick and prompt changes corresponding with the signals received through the wireless apparatus or other sound devices acting through the funnel 30. The baffle 40 should be spaced a sufficient distance from the end of the tube 36 to permit the fluid acting against the diaphragm to escape freely as soon as the jet is disturbed so that the bulk of the fluid strikes the baffle or dissipates itself about the frame 27 instead of passing through the port 41 leading to the diaphragm. By making the passage 42 relatively large the escape of the fluid is rendered easy and quick and the diaphragm is permitted to quickly change its direction, thereby making or breaking the contact of the relay. 115 120 125 130

The use of a plurality of tanks for the fluid enables me to eliminate sound vibrations coming from the pump or other source that might disturb the operation of the relay, and it is particularly important to have the connections between the tanks and between the tanks and the apparatus extend well into the tanks as illustrated in Fig. 3 so as to prevent the transmission of any sound vibrations through the passages. By using the manometer or other pressure indicating device it becomes possible to properly adjust the pressure at the nozzle so as to produce a jet suitable to the particular work. The screw 22 by which the valve 21 is regulated to control the escape of pressure from the tank 14 may be equipped with a knob 81 extending above the cover 71. In like manner the screw 49 may have a similar knob 82 located above the cover in a convenient reach for tuning the relay.

I am aware that changes may be made in the form, construction and arrangement of the invention, as set forth in the selected embodiment herein, without departing from the scope or sacrificing any of its material advantages, and I therefore reserve the right to make all such changes as fairly fall within the scope of the following claims:

I claim:

1. The combination of means for producing a jet, a movable medium in the path of said jet, a tubular passage adjacent to the medium through which said jet passes,

means for impressing sound waves on said jet to produce varying phases therein, and a member in front of said passage having a port of smaller area than the passage and aligned with said jet.

2. The combination of means for producing a jet, a nozzle for delivering the jet, a movable medium adapted to be acted upon by said jet, a passage aligned with said nozzle and leading to said medium, means for impressing sound waves on said jet to produce varying phases therein, and a baffle interposed between said last named means and said passage and having a port aligned with said jet.

3. The combination of means for producing a jet, a nozzle for delivering the jet, a movable medium adapted to be acted upon by said jet, a passage aligned with said nozzle and leading to said medium, means for impressing sound waves on said jet to produce varying phases therein, and a baffle interposed between said last named means and said passage and having a port aligned with said jet and of smaller diameter than said passage.

4. The combination of means for producing a jet including a nozzle, a movable medium adapted to be acted upon by said jet, a tube aligned with said nozzle and having a passage of greater area than said nozzle

leading to said medium, means for impressing sound waves on said jet adjacent to said nozzle, and a baffle spaced from said tube and having a port aligned with said passage and said nozzle.

5. The combination of means for producing a jet including a nozzle, means adjacent to the nozzle for impressing sound waves on said jet to produce varying phases therein, a diaphragm adapted to be acted upon by said jet, a tube aligned with said nozzle and having a relatively large passage leading to said diaphragm, and a baffle between said tube and said nozzle having a port aligned therewith.

6. The combination of means for producing a jet including a nozzle, means for impressing sound waves on said jet adjacent to said nozzle, a diaphragm adapted to be acted upon by said jet, a tube aligned with said nozzle and having a relatively large passage leading to said diaphragm, a baffle carried by said tube spaced from the receiving end thereof and having a port of smaller area than the passage in alignment therewith.

7. The combination of means for producing a jet including a nozzle, means for impressing sound waves on said jet adjacent to said nozzle, a tube aligned with said nozzle having a relatively large passage therethrough, a baffle between said tube and said nozzle, a disk connected to said tube and having a dish-face, and a diaphragm extending across said dish-face.

8. The combination of means for producing a jet, a medium adapted to be moved to and fro by said jet, a resiliently mounted contact adapted to be moved by said medium, and a friction controlled contact cooperating with said resiliently mounted contact.

9. The combination of a movable medium, means for directing a varying jet against said medium, a resiliently mounted contact moved by said medium, spaced conducting and non-conducting surfaces on said contact, a movable contact between said conducting and non-conducting surfaces, and friction devices to resist any movement of said movable contact.

10. The combination of a movable medium, means for directing a varying jet against said medium, a resiliently mounted contact moved by said medium, spaced conducting and non-conducting surfaces on said contact, a movable contact between said conducting and non-conducting surfaces, and a pivoted arm carrying said movable contact and means to resist movement of said pivoted arm.

11. The combination of a movable medium, means for directing a varying jet against said medium, a resiliently mounted contact moved by said medium, spaced con-

ducting and non-conducting surfaces on said contact, a movable contact between said conducting and non-conducting surfaces, a pivoted arm carrying said movable contact, and adjustable friction devices for resisting movement of said pivoted arm.

12. The combination of a movable medium, means for directing a varying jet against said medium, a resiliently mounted contact moved by said medium, spaced conducting and non-conducting surfaces on said contact, a movable contact between said conducting and non-conducting surfaces, a pivoted arm carrying said movable contact, and a friction device acting on said arm to resist pivotal movement thereof.

13. The combination of a diaphragm, means for directing a jet against said diaphragm, a tube having a relatively large passage therein through which said jet passes to said diaphragm, a baffle spaced from the end of said tube in the path of said jet, means for impressing sound waves on said jet, a resiliently mounted contact moved by said diaphragm, and a pivotally mounted contact moved by said resiliently mounted contact.

14. The combination of means for producing a jet including a nozzle, means for impressing sound waves on said jet adjacent to the nozzle, a tube having a relatively large passage aligned with said jet and communicating with a diaphragm chamber, a diaphragm across said chamber, a baffle interposed between said tube and said nozzle having a relatively small passage for said jet, a resiliently mounted contact cooperating with said diaphragm, a floating contact cooperating with said resiliently mounted contact, and friction devices adapted to resist any movement of said floating contact.

15. A relay comprising a source of fluid under pressure, a plurality of tanks, and connections between the tanks including tubes extending inwardly from the walls of the tanks.

16. A relay comprising a source of fluid under pressure, a plurality of connected tanks, one of said tanks having an outlet and a valve for regulating the flow from said outlet.

17. A relay comprising a source of fluid under pressure, a plurality of connected tanks, the tank remote from said source having an outlet therein, a valve for controlling said outlet, and means for indicating the fluid pressure in said remote tank.

18. A relay comprising a source of fluid under pressure, a plurality of tanks, means

for connecting the tanks, the tank remote from the source having an outlet and a valve for controlling said outlet, and a manometer for indicating the pressure in said remote tank.

19. A relay comprising a casing, a plurality of tanks in said casing, means for connecting the tanks together, means for connecting one of said tanks with a source of fluid under pressure, an outlet for one of said tanks, means projecting through said casing for controlling said outlet, and a manometer for reading the pressure in said tank having an outlet, said casing having an opening through which said manometer is visible.

20. The method of making sounds of relatively small volume readily perceptible which consists in subjecting a movable medium to the action of a fluid jet directed through a passage of relatively great area, impressing sound vibrations on said jet to produce varying phases and baffling certain phases of said jet adjacent to the entrance to the passage.

21. The method of making sounds of relatively small volume readily perceptible which consists in impressing them upon a sensitive jet directed against a movable medium, and controlling the flow of current in an electric circuit by changes in the direction of movement of said medium.

22. The method of making sounds of relatively small volume readily perceptible which consists in impressing them upon a sensitive jet, directing the jet against a movable medium through aligned passages of different size, and controlling the flow of current in an electric circuit by changes in direction in the movement of said medium.

23. The method of making sounds of relatively small volume readily perceptible which consists in impressing them upon a sensitive jet adapted to assume varying phases under the energy of the impressed sounds, directing the jet through aligned passages of different sizes against a movable medium, and operating a relay by changes in direction in the movement of said medium.

24. The combination of means for producing a jet including a nozzle, means for impressing sound waves on said jet adjacent to the nozzle, a movable medium spaced from said nozzle, and means between said movable medium and said nozzle providing aligned passages of different diameters for said jet.

RAY E. HALL.
